UNITED STATES PATENT OFFICE.

THOMAS C. CLARK, OF CAMBRIDGE, OHIO.

FLAG-STAFF HOLDER.

SPECIFICATION forming part of Letters Patent No. 416,901, dated December 10, 1889.

Application filed April 12, 1889. Serial No. 307,046. (No model.)

To all whom it may concern:

Be it known that I, THOMAS C. CLARK, a citizen of the United States, residing at Cambridge, in the county of Guernsey and State of Ohio, have invented certain new and useful Improvements in Flag-Staffs; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to signaling devices of that class which use different-colored flags, and which are used on cars, railroad-locomotives, boats, and vehicles of any description, and by station-keepers, telegraph-operators, 20 and watchmen.

The object of the invention is to provide a case that will keep the flags separated and which will form part of the staff, the flags being contained in separate pockets or apart- 25 ments formed in the case.

The improvement consists of the novel features which will be hereinafter more fully described and claimed, and shown in the accompanying drawings, in which—

30 Figure 1 is a side view of my invention. Fig. 2 is a vertical section on the line X X of Fig. 1, showing the signal displayed by dotted lines. Fig. 3 is a top plan view of the case, the cap being removed. Fig. 4 is a detail 35 view of the flag-staff and holder. Fig. 5 is a top plan view of the cap.

The case A, which may be of any required size and dimensions, has a series of longitudinal pockets or apartments B, the number 40 corresponding with the number of flags to be housed, which extend through one end of the case and have slots b extending through the sides thereof. Each pocket or apartment is provided with a holder C, that has a socket 45 at its upper end, and which is provided with a lateral stem d, which projects through the slot b sufficiently far to be grasped by the fingers for moving the said holder in the pocket. The staff D is reduced near its up- 50 per end, and the flag E is adapted to be wound on said reduced portion, so as to come within the sides or diameter of the staff,

whereby the staff and flag can move freely in and out of the pocket. The lower end of the staff is reduced to enter the socket in the 55 holder. When the staff is projected and the flag displayed, it is held by the stem d, resting in the notch g, projecting from the side of the slot b near the upper end of the case.

The cap F, fitted on the end of the case, has 60 an opening f, which is adapted to register with the pockets, and through which the flag-staff is projected. The pivoted cover H is adapted to protect the opening f and shed rain and snow, and the notch h in the edge 65 of the cover is adapted to receive the flag-staff and hold it from dropping from the case, the flag-staff being grooved at I to fit in the said notch h. Where the signal is designed to be permanently attached to the pilot of 70 an engine or other support, it will be provided with a base J, which is screwed on the case A, and which is fastened to the said support.

Having thus described my invention, what I claim, and desire to secure by Letters Patent, 75 is—

1. The herein-described signal device comprising the case having a series of separate and independent pockets formed longitudinally therein, each pocket having a slot in 80 its side and a lateral notch communicating with the said slot, and the series of flag-staffs having flags inserted in said pockets and having stems to work in said slots and rest in the lateral notches, substantially as and 85 for the purpose described.

2. In a signal-case having a longitudinal pocket and a slot in its side communicating with the pocket, the combination of the holder placed in the pocket and having a stem to 90 work in the said slot, and the flag-staff inserted in the said pocket and adjustable therein with the holder, substantially as and for the purpose described.

3. The combination, with the signal-case 95 having a series of pockets, of the rotatable cap having a single opening that is adapted to be brought in register with either of said pockets, substantially as and for the purpose described.

4. The combination, with the signal-case having a series of pockets and the flag-staff, of the cap having an opening and the pivoted cover adapted to close said opening and en-

gage with the flag-staff, substantially as and for the purpose described.

5. The herein shown and described signal device, composed of the case supported on a suitable base and having a series of longitudinal pockets and slots, the latter having side notches, the holders inserted in the pockets and having lateral stems, the flag-staffs having the flags wound on reduced portions of 10 the said staffs, and the cap having an open-

ing and a pivoted cover that is adapted to close said opening and engage with the flag-staff, substantially as set forth.

In testimony whereof I affix my signature in presence of two witnesses.

THOMAS C. CLARK.

Witnesses:
